United States Patent

Des. 241,365
Patented Sept. 7, 1976

241,365

DIAMOND PENDANT

Alfred Joseph Durante, Forest Hills, N.Y., assignor to Cartier, Inc., New York, N.Y.

Filed Mar. 3, 1975, Ser. No. 554,517

Term of patent 14 years

Int. Cl. D11—01

U.S. Cl. D11—79

FIG. 3

FIG. 1

FIG. 2

FIG. 4

FIG. 1 is a front elevational view of a diamond pendant showing my novel design, the rear being identical;

FIG. 2 is a side elevational view of the diamond pendant shown in FIG. 1, both sides being identical;

FIG. 3 is a top elevational view of the diamond pendant shown in FIG. 1; and

FIG. 4 is a bottom plan view of the diamond pendant shown in FIG. 1.

I claim:

The ornamental design for a diamond pendant, as shown and described.
